UNITED STATES PATENT OFFICE.

EDWARD KENER, JR., OF BUFFALO, NEW YORK.

AUTOMATIC SHUT-OFF MECHANISM FOR INCINERATOR VALVES.

Application filed February 12, 1924. Serial No. 692,394.

To all whom it may concern:

Be it known that I, EDWARD KENER, Jr., a citizen of the United States, residing at Buffalo, in the county of Erie and State of New York, have invented a new and useful Improvement in Automatic Shut-Off Mechanism for Incinerator Valves, of which the following is a specification.

This invention relates to an automatic shut-off mechanism for the valves which control the supply of fuel to incinerators and similar installations and has for its object the provision of such a mechanism which can be set manually to hold the valve open until the high pile of refuse has burned down to a low pile of ashes and then operates automatically to close the valve so that the flame is extinguished, thereby conserving fuel and avoiding undue heating of the compartment containing the incinerator.

In the accompanying drawings: Figure 1 is a fragmentary section of an incinerator embodying my improvement and showing the part in one position. Figure 2 is a horizontal section taken on line 2—2, Fig. 1. Figures 3 and 4 are views similar to Figure 1 and showing the parts in different positions. Figures 5 and 6 are fragmentary cross sections, on an enlarged scale, taken on the correspondingly numbered lines in Figure 3.

Similar characters of reference indicate like parts throughout the several views.

The numeral 10 represents the refuse receptacle or combustion chamber which receives the garbage or other material which is to be destroyed by cremation. This material is introduced into this chamber through a filling inlet 11 in its upper part which is normally closed by a door 12 and the non-combustible gases resulting in the destruction of the garbage are carried from the top of the refuse chamber through a flue to a chimney leading to the exterior of the building. The bottom of the mass of garbage rests on a grate 13 which may be dumped for discharging the ashes into a pit 14 below the refuse chamber, this pit having a discharge opening which may be closed by a door 15. The grate is preferably constructed in two sections and between the same is arranged a hollow bridge 16 which has a V-shaped top and is open on its underside and forms a housing. Arranged centrally within the refuse chamber is a vertically telescopic burner which is composed of a plurality of sections

17, 18, 19 and 20 of progressively smaller diameter from the lowermost to the uppermost. The lower end of the lowermost burner section is arranged in a central opening 21 in the central part of the bridge and provided with an outwardly facing external shoulder 22 adapted to engage with the underside of the bridge for limiting its upward movement. Each of the upper burner sections is provided at its lower end with an outwardly facing external shoulder 23 which is adapted to engage with an inwardly facing internal shoulder 24 at the upper end of the next lower burner section for the purpose of limiting the upward extension of the burner sections. The latter are thus extended by any suitable means preparatory to filling the combustion chamber with refuse or garbage and thereafter the top of the pile of garbage is engaged by a spreading disk or plate 25 which is provided on its underside by spacing ribs 26 and is connected by a link 27 or otherwise with the upper end of the uppermost burner section. This uppermost burner section is provided with perforations so as to permit the gas which is supplied at the lower end of the lowermost section to issue laterally from the uppermost burner section and burn in a flame which overspreads the top of the pile of garbage below the spreading plate and thereby consumes the pile from the top down and the gases issuing therefrom. As the consumption of the garbage or refuse progresses the top of the pile gradually lowers and as the spreading plate rests thereon by gravity the same drops by gravity in the same measure and the burner sections also gradually telescope one within the other. The descent of the several burner sections is limited by engagement with the gas delivery pipe 28 which is arranged lengthwise below the bridge and is provided centrally with an upwardly projecting nozzle 29 which directs the gas issuing therefrom upwardly into the center of the burner. The gas delivery pipe is connected at its outer end with a gas supply pipe 30 by means of a valve 31 having a rotatable plug 32 which controls the passage through this valve, and a rock arm 33 on this plug for turning the same into an open or closed position. When the pile of refuse has been completely burned and reduced to a low pile of ashes the several sections of the burner have been completely telescoped and most of them rest at their lower ends on the

gas delivery pipe while the spreading plate rests on top of the small pile of ashes, as shown in Figure 3.

The mechanism for automatically shutting off the gas valve 31 in accordance with my invention is dependent for its operation upon the completion of the nesting action of the several burner sections which occurs when the pile of ashes has reached its lowest practical level. In its preferred construction this shut-off mechanism is constructed as follows:

The numeral 34 represents an upright supporting plate which for convenience may be mounted on the side of the gas delivery pipe and provided at its inner end with a vertical flange 35 having a guide opening 36. The numeral 37 represents a longitudinally reciprocating and vertically oscillating latch which slides with its inner end in the guide opening 36 while its outer end is connected by a link or rod 38 with the rock arm 33. Intermediate of its ends the latch engages its upper edge with a fulcrum pin or lug 39 which is arranged on the supporting plate. On its outer part this latch is provided with an upwardly projecting tension lug 40 which together with the body of the latch forms an angular lever. This lug is connected with the inner part of the supporting plate by a spring 41 arranged lengthwise above the latch and the fulcrum pin so that the tension of this spring not only tends to pull the latch horizontally inward, but also to tilt the same so that its inner or front end is depressed and its outer or rear end is elevated. On its inner end part the latch is provided with an L-shaped locking slot having a horizontal lower part 42 and a vertical front part 43 which extends upwardly from the inner or front end of said horizontal part and forms an inwardly facing shoulder 44 between these slot portions.

Arranged on the supporting plate and projecting into the locking slot is a locking lug or abutment 49 which is mounted on the supporting plate. Pivotally mounted on the central part of the gas delivery pipe by means of a pin 45 is a vertically swinging trip lever having an outer or rear arm 46 adapted to engage with the underside of the front end of the latch and an inner or front arm 47 arranged in the path of the innermost member of the telescopic sections of the burner.

For the purpose of setting the shut-off mechanism for opening the gas supply valve after the refuse chamber has been filled and the burner has been distended and the spreading plate engaged with the top of the pile of refuse, the handle 50 of the valve plug is turned horizontally outward so as to open this valve and permit gas to flow up through the burner and issue from the

upper end of the same where it is ignited and burns in a flame over the refuse. Upon thus opening the gas valve the latch is drawn outwardly due to the link connection with the rock arm of the valve, and at the same time the latch is turned so that the shoulder 44 of the latch engages with the locking lug 49 and holds the valve in its open position. At this time the trip lever is turned by gravity so that its outer or rear arm is depressed and its inner or front arm is elevated, as shown in Figure 1. The parts remain in this position and the gas continues to flow to the outlet of the burner until the refuse is entirely consumed from the top down and the height of the pile is finally reduced to a low pile of ashes at which time the burner sections are wholly nested and rest on the gas delivery pipe. As the innermost burner section approaches closely to its lowermost position the lower end of the same engages with the same whereby the outer or rear arm of this lever is caused to engage the underside of the front end of the latch and begin to lift the same, as shown in Figure 4. During the last part of the downward movement of the innermost section of the burner and before the same rests on the gas delivery pipe the trip lever has been turned sufficiently to disengage the latch from the locking lug, and the instant this occurs the spring 41 pulls the latch inwardly until the outer end of the longitudinal part of the locking slot engages the locking lug, as shown in Figure 3, thereby causing the plug of the gas valve to be turned in the direction for closing the same and shutting off the further supply of gas to the burner. The supply of gas is by this means automatically arrested when the refuse has been reduced to ashes thereby avoiding the necessity of watching the incinerator for this purpose and also effecting a saving in gas as well as undue wear on the apparatus.

In the preferred construction of the linkage 38 the same is made up of a plurality of links, the outermost one 381 of which has its outer end curved as shown in Figure 2. By this it is possible to produce a straight outward pull from the valve arm 33 on the latch 37 through the medium of the linkage for setting the shut-off mechanism when opening the valve, in which case the linkage is arranged alongside of the valve, as shown in full lines in Figure 2, also permitting a straight inward pull by the latch on the valve arm for closing the valve automatically and also permitting the valve plug to be turned into a closed position independently of the latch when it is desired to stop burning the pile of refuse before the same is entirely consumed. When the valve is thus closed manually, as just described, the linkage simply folds or doubles up the requisite extent to permit the valve arm 33 to turn

without disturbing the set position of the latch.

I claim as my invention:

1. An incinerator comprising a combustion chamber adapted to receive the pile of refuse to be destroyed, a gas burner adapted to provide a flame for consuming said refuse, and having a member which descends by gravity as the level of the pile of refuse lowers while being consumed by said flame, and automatic means for shutting-off said valve which are actuated by the descent of said member to its lowered position. 70
2. An incinerator comprising a combustion chamber adapted to receive the pile of refuse to be destroyed, a gas burner adapted to provide a flame for consuming said refuse, and having a member which descends by gravity as the level of the pile of refuse lowers while being consumed by said flame, and automatic means for shutting-off said valve which are actuated by the descent of said member to its lowered position. 80
3. An incinerator comprising a combustion chamber adapted to receive the pile of refuse to be destroyed, a gas burner adapted to direct a flame against said refuse for consuming the same and having a movable member supported by the top of said pile and to descend therewith as the same is reduced to ashes, a conduit for supplying gas to said burner, a valve arranged in said conduit and having a rotary plug for controlling the flow of gas and an arm on said plug, and automatic shut-off mechanism which is actuated by said movable burner member and operates to close said plug when said burner member reaches its lowermost position. 90
4. An incinerator comprising a combustion chamber adapted to receive the pile of refuse to be destroyed, a gas burner adapted to direct a flame against said refuse for consuming the same and having a movable member supported by the top of said pile and to descend therewith as the same is reduced to ashes, a conduit for supplying gas to said burner, a valve arranged in said conduit and having a rotary plug for controlling the flow of gas and an arm on said plug, a latch connected with said arm and having an L-shaped slot forming a forwardly facing locking shoulder, a stationary abutment adapted to be engaged by said shoulder and hold said latch in its rearward position and said plug open, a spring connected with said latch and tending to move the same forward when free, and means actuated by the descent of said movable burner member and adapted to disengage said latch from said abutment. 100
5. An incinerator comprising a combustion chamber adapted to receive the pile of refuse to be destroyed, a gas burner adapted to direct a flame against said refuse for consuming the same and having a movable member supported by the top of said pile and to descend therewith as the same is reduced to ashes, a conduit for supplying gas to said burner, a valve arranged in said conduit and having a rotary plug for controlling the flow of gas and an arm on said plug, a latch connected with said arm and having an L-shaped slot forming a forwardly facing locking shoulder, a stationary abutment adapted to be engaged by said shoulder and hold said latch in its rearward position and said plug open, a spring connected with said latch and tending to move the same forward when free, and means actuated by the descent of said movable burner member and adapted to disengage said latch from said abutment. 105
6. An incinerator comprising a combustion chamber adapted to receive the pile of refuse to be destroyed, a gas burner adapted to direct a flame against said refuse for consuming the same, and having a movable member supported by the top of said pile and to descend therewith as the same is reduced to ashes, a conduit for supplying gas to said burner, a valve arranged in said conduit and having a rotary plug for controlling the flow of gas and an arm on said plug, a latch connected with said arm and having an L-shaped slot forming a forwardly facing locking shoulder, a stationary abutment adapted to be engaged by said shoulder and hold said latch in its rearward position and said plug open, a spring connected with said latch and tending to move the same forward when free, and means actuated by the descent of said movable burner member and adapted to disengage said latch from said abutment. 110
7. An incinerator comprising a combustion chamber adapted to receive the pile of refuse to be destroyed, a gas burner adapted to direct a flame against said refuse for consuming the same, and having a movable member supported by the top of said pile and to descend therewith as the same is reduced to ashes, a conduit for supplying gas to said burner, a valve arranged in said conduit and having a rotary plug for controlling the flow of gas and an arm on said plug, a latch connected with said arm and having an L-shaped slot forming a forwardly facing locking shoulder, a stationary abutment adapted to be engaged by said shoulder and hold said latch in its rearward position and said plug open, a spring connected with said latch and tending to move the same forward when free, and means actuated by the descent of said movable burner member and adapted to disengage said latch from said abutment. 115
8. An incinerator comprising a combustion chamber adapted to receive the pile of refuse to be destroyed, a gas burner adapted to direct a flame against said refuse for consuming the same, and having a movable member supported by the top of said pile and to descend therewith as the same is reduced to ashes, a conduit for supplying gas to said burner, a valve arranged in said conduit and having a rotary plug for controlling the flow of gas and an arm on said plug, a latch connected with said arm and having an L-shaped slot forming a forwardly facing locking shoulder, a stationary abutment adapted to be engaged by said shoulder and hold said latch in its rearward position and said plug open, a spring connected with said latch and tending to move the same forward when free, and means actuated by the descent of said movable burner member and adapted to disengage said latch from said abutment. 120
9. An incinerator comprising a combustion chamber adapted to receive the pile of refuse to be destroyed, a gas burner adapted to direct a flame against said refuse for consuming the same, and having a movable member supported by the top of said pile and to descend therewith as the same is reduced to ashes, a conduit for supplying gas to said burner, a valve arranged in said conduit and having a rotary plug for controlling the flow of gas and an arm on said plug, a latch connected with said arm and having an L-shaped slot forming a forwardly facing locking shoulder, a stationary abutment adapted to be engaged by said shoulder and hold said latch in its rearward position and said plug open, a spring connected with said latch and tending to move the same forward when free, and means actuated by the descent of said movable burner member and adapted to disengage said latch from said abutment. 125
10. An incinerator comprising a combustion chamber adapted to receive the pile of refuse to be destroyed, a gas burner adapted to direct a flame against said refuse for consuming the same, and having a movable member supported by the top of said pile and to descend therewith as the same is reduced to ashes, a conduit for supplying gas to said burner, a valve arranged in said conduit and having a rotary plug for controlling the flow of gas and an arm on said plug, a latch connected with said arm and having an L-shaped slot forming a forwardly facing locking shoulder, a stationary abutment adapted to be engaged by said shoulder and hold said latch in its rearward position and said plug open, a spring connected with said latch and tending to move the same forward when free, and means actuated by the descent of said movable burner member and adapted to disengage said latch from said abutment. 130

duit and having a rotary plug for controlling the flow of gas and an arm on said plug, a latch connected with said arm and having an L-shaped slot forming a forwardly facing locking shoulder and an upwardly projecting tension lug, a spring connected with said lug, a fulcrum pin on which said latch is adapted to slide and turn, a stationary abutment adapted to be engaged by said shoulder and hold said latch in its rearward position, and means actuated by the descent of said movable burner member and adapted to disengage said latch from said abutment.

8. An incinerator comprising a combustion chamber adapted to receive the pile of refuse to be destroyed, a gas burner adapted to direct a flame against said refuse for consuming the same and having a movable member supported by the top of said pile and to descend therewith as the same is reduced to ashes, a conduit for supplying gas to said burner, a valve arranged in said conduit and having a rotary plug for controlling the flow of gas and an arm on said plug, a latch connected with said arm and having an L-shaped slot forming a forwardly facing locking shoulder and an upwardly projecting tension lug, a spring con-

nected with said lug, a fulcrum pin on which said latch is adapted to slide and turn, a stationary abutment adapted to be engaged by said shoulder and hold said latch in its rearward position, and a trip lever having one of its arms arranged in the path of said movable burner member and to be shifted thereby and adapted to engage its other arm with said latch for disengaging the same from said abutment.

9. An incinerator comprising a combustion chamber adapted to receive a pile of refuse to be consumed, a burner for directing a flame toward said pile, a fuel supply conduit for supplying fuel to said burner, a valve in said conduit for controlling the passage of fuel and having a rotary plug, a handle on said plug for operating the same manually, and means for closing said plug automatically comprising a latch, an abutment which is adapted to be engaged by said latch for holding the latter in a set position, means responsive to a lowering of the height of said pile for disengaging said latch from said abutment, and a link connecting said latch with said arm.

In testimony whereof I affix my signature.
EDWARD KENER, Jr.
